PUMPING UNIT

Reinhold A. Norling, Aurora, Ill., assignor to Independent Pneumatic Tool Co., Chicago, Ill., a corporation of Delaware

Application December 5, 1932, Serial No. 645,745

7 Claims. (Cl. 103—87)

This invention relates to pumps, and more particularly to a portable power driven pumping unit adapted to be lowered into a pit, trench, basement or other receptacle for pumping water or other liquids therefrom.

The general purpose and object of my invention is to provide a self-contained pumping unit in the nature of a tool capable of being handled and used as such and yet rugged and sturdy in its construction to withstand the heavy duties imposed on pumping devices of this character in outdoor and other construction and building work.

Other and further objects of my invention are to provide a pumping unit driven pneumatically, as by a compressed air motor; to prevent pressure fluid leaking from the motor about the pump shaft entering the pump casing to render the pumping element air bound; to make the stuffing box for the pump shaft accessible for adjustment from the exterior of the tool; to provide a regulator on the pump device for the throttle valve so that the speed of the motor may be regulated to the desired rate of discharge of water from the pit to prevent wasting of the air and excessive wear on the motor and the pump; to have the exhaust for the motor discharging upwardly to prevent disburting the water at the intake for the pump at the lower end of the unit; to close the exhaust outlet by a check valve to prevent water entering the motor to stop the same; and to provide a check valve on the discharge side of the pump to prevent flooding of the pit through the pump when the motor is stopped.

The invention consists further in the matters hereinafter described and claimed.

In the accompanying drawings:—

Fig. 1 shows the pump device of my invention in its position of use in a pit or trench.

Fig. 2 is an enlarged sectional view of the pump device taken longitudinally through the same;

Fig. 3 is a vertical sectional view, with parts in elevation, taken on line 3—3 of Fig. 2;

Figs. 4 and 5 are horizontal sectional views taken on lines 4—4 and 5—5, respectively, of Fig. 2;

Figs. 6 and 7 are elevational views showing details of construction to be hereinafter described;

Fig. 8 is a bottom plane view of the pump primer; and

Fig. 9 is a horizontal section taken on line 9—9 of Fig. 2.

The pump device of my invention, as shown in the drawings, comprises generally three axially aligned and secured together pumping, motor and control valve sections, whereby the device is a

self-contained unit or tool capable of being lowered as such into a pit or trench 1, as shown in Fig. 1, for pumping water therefrom. The upper or top section 2 of the device is the control valve section and is provided with an eye 3 whereby the handling rope or cable may be connected with the device for lowering and suspending it in the pit.

The motor section 4 which is the intermediate of the sections is equipped with a fluid pressure motor 10 for rotating the pump in the lower or pump section 5. The motor, as shown in Figs. 2 and 5, is of the rotary type having a rotor 6 provided with radial slots 7 in which operate blades 8 forming the piston elements of the motor. The blades work 13 against the inner surface of the rotor chamber 9 in which the rotor is eccentrically mounted. Chamber 9 has inlet ports 10 on one side and exhaust ports 11 on the other, as shown in Fig. 5. The exhaust ports open into an exhaust chamber 12 provided by the outer casing 4 of the motor section. Chamber 12 opens into an exhaust manifold 13 extending upwardly therefrom to the top of the pump device where the manifold is equipped with a downwardly seating gravity closing check valve 14, as shown in Fig. 3. Valve 14 is guided by a stem 15 slidably fitting in a support 16 which is in the form of a cross-piece open on both sides for the escape of the exhaust.

The control section 2 is provided at its upper end with a tapped inlet passage 17 to which the compressed air supply conduit or hose 18 is attached as shown in Fig. 1. A throttle valve in the form of a turning plug 19 is fitted in said passage and controls the flow of pressure fluid therethrough. The stem 20 of the valve projects outside of the casing section 2 and is equipped with a control handle or regulator 21 carrying a spring pressed plunger 22 co-operable with a series of apertures 23 to hold the valve in any of a number of adjusted positions. These apertures, as shown in Fig. 7, are arranged along the arc of movement of the outer end of the handle and are disposed between stops 24, 24 which limit the extent of movement of the handle to full open and full closed positions of the valve. The apertures may be provided in the casing comprising the section 2, the latter having a web for the purpose as shown in Fig. 7.

The regulator construction shown and described enables the throttle valve 19 to be set at the position desired to regulate the speed of the motor, and thus the speed of the pump which it actuates. Thus, the valve may be set to regulate the pump speed according to the seepage

into the pit where the pump is used, preventing the motor from running idle when the seepage is slow and saving air and wear on the motor. Moreover, with the regulator carried by the pump device, it is accessible to the workman in the pit, and thus the motor speed may be readily and easily controlled to keep the water in the pit at a pre-determined height without undue racing of the motor.

The check valve 14 closes the upper end of the exhaust manifold 13 and prevents water getting into the motor should the pump be completely submerged when in use, as is likely to occur when first lowering the pump into the pit. The manifold pointing and discharging upwardly and being at the extreme upper end of the device prevents the exhaust gases leaving the manifold from disturbing the water at the inlet end of the pump, which inlet end, to be presently described, is at the extreme lower end of the unit.

Live air is admitted to the motor from the inlet 17 through passages 25 which connect the inlet chamber 26 at the valve 19 with a chamber 27 at the bushing 28 for the governor controlled valve 29. Bushing 28 opens into a supply passage 30 serving the inlet ports 10 of the rotor chamber. The opening and closing movements of the valve 29 are automatically controlled by a spring 31 and a governor device 32 rotated by the rotor 6 and acting on the valve through a lever 33 as shown.

The rotor 6 is provided with a shaft extension 34 extending into the pump section 5 and connected with the pump shaft 35 in that section by a coupling element 36. The pump shaft is journaled in the section 5 in a bushing 37 and an anti-friction bearing 38, respectively. The bearing 38, which is of the ball type, holds the pump shaft 35 from endwise movement.

Bearing 38, as shown in Fig. 2, is supported in a stuffing box housing 39 slidably fitted in the pump shaft housing 5 and held in place against a shoulder or seat 40 by a spacing sleeve 41. The latter also holds the ball bearing 38 in place, and fits between the upper end of the housing 39 and bottom plate 42 of the rotor chamber. The housing 39 is fitted with a packing material 43 fitting about the pump shaft 35 below the bearing 38 to prevent water entering the motor from the pump housing and also to prevent air or pressure fluid leaking from the motor into the pump casing to interfere with the pumping action of the pump. The packing material 43 is compressible through a nut 44 screwed into the lower end of the stuffing box housing and having an engageable head with slots or openings 45, as shown in Fig. 2.

The nut 44 may be reached for adjustment through an opening 46 in the pump housing 5. This opening, as shown in Fig. 4, is disposed between two of the longitudinally extending ribs or webs 47 on the outer side of the pump housing. A cover 48 is provided for the opening, the cover fitting against the outer side of the pump housing and having hook shaped portions 49, 49 at its side edges to fit over the webs and slidably support the cover thereon. A screw 50 carried by the cover and engageable with one of the webs holds the cover in place. Loosening the screw 50 and sliding the cover endwise uncovers the opening 46 to permit access to the nut 44 for compressing the packing 43. Thus, the stuffing box structure may be reached for adjustment without taking anything apart. The

opening 46, as shown in Fig. 6 is disposed directly opposite the head of the nut.

The cover 48 prevents shavings, pieces of rope and other articles which may be in the water in which the pump unit operates, from getting into the pump housing through the opening to wind about the pump shaft. The cover is provided with one or more vent openings 51 to permit the escape of any air leakage past the packing and thus prevent this air from entering the pump to render it air bound.

The pump which is at the extreme lower end of the unit comprises an impeller 52 located in casing 53 carried by the pump housing 5. The impeller is connected to the pump shaft 35 by a taper fit and a key, as shown in Fig. 2. This makes the impeller rigid with the pump shaft and causes it to run true with said shaft. The impeller as shown in Fig. 9, has upper and lower circular plates, between which are vanes 54 which as the impeller is rotated draw liquid into the impeller through its intake 55 and discharge the liquid from the periphery into the housing 53, the latter surrounding the impeller and provided with an upwardly directed discharge opening 56.

The intake 55 is formed by a circular flange 57 depending from the lower plate of the impeller. Surrounding this flange is a loosely fitting wear-bushing 58, the latter being held in place by the primer 59 through a bolt 60. The bolt 60 is engaged with the pump shaft 35 and when tightened clamps the primer 59 against the lower end of the bushing 58 and seats the upper edge of the bushing against a shoulder on the lower plate of the impeller about the flange 57, as shown in Fig. 2.

A packing ring 61 engages the outer side of the bushing 58 to prevent leakage from the inside of the pump housing 53. The packing is filled in a groove in the cover plate 62 for the lower side of the pump housing, said plate being secured to the pump housing by bolts, one of which is shown at 63 in Fig. 2. Cover plate 62 is provided with an upstanding annular flange 64 surrounding the periphery of the impeller to prevent gravel and dirt taken in with the water from collecting around the bushing 58 to cause excessive wear of the same.

The primer 59, as shown in Fig. 8, is in the form of a casting having a fluid passage 65 therethrough in constant communication with the intake 55 of the impeller. At one side of this passage is a downwardly extending scoop 66 which serves in the rotation of the pump to deliver water to the impeller through its intake 55 for priming the pump. After the water level drops below the cover plate 62, air enters the pump through its intake 55. The primer, however, extending below the impeller, is still in the water and having the scoop, forces the water into the impeller, displacing the air and starting the pump. The primer is an important feature of my invention and permits operation of the pump even when the intake 55 is above the water level in the pit.

Surrounding the primer is a screen 67 for the purpose of preventing stones and other articles entering the pump. The screen fits between the cover plate 62 and a base plate 68 which covers the pump inlet. Plate 68 is secured to plate 62 by the bolts 63, the upper plate having a depending boss or lug 69 about each bolt to space the plates apart as shown.

A discharge fitting 70 is fitted to the impeller casing 53 at its discharge port 56 and is equipped

5 with a non-return check 11 for said port. This valve prevents the water flowing back into the pit through the pump to flood the pit when the motor is not running. As the pump shown is capable of raising water as high as 100 feet, the discharge pipe 72 connected to the fitting 10 is substantially two inches in diameter and considerable water would flow back into the pit except for the use of the check valve.

10 The construction shown and described provides an effective and efficient pump device for pumping water from pits, trenches, basements and the like. The device is a self-contained unit, capable of being handled as such in use.

15 The primer automatically primes the pump and moreover supplies water thereto even when the water level in the pit drops below the intake opening of the impeller. Thus, the pump may be used to remove seepage from a trench or pit, the 20 pump speed being adjusted through the setting of the valve control to that necessary to remove the seepage. With the valve control on the pump device, it is accessible to the workman in the pit, and thus the pump speed may be adjusted to accord to the desired rate of discharge from the 25 pit.

30 The opening 46 in the pump housing 5 has the dual purpose of permitting access to be had to the stuffing box for adjusting it to prevent leakage of water from the pump into the motor casing and also to vent the pump housing should air leak into the same from the motor casing. This prevents the air used to drive the motor from entering the impeller casing to render the same 35 air bound.

35 The packing assembly for the intake of the pump is also an important feature of my invention. The pump is used for pumping all kinds of dirty water and excessive wear is at the bushing 58. After the bushing has worn down to a certain extent, the pump is likely to function improperly due to the escape of water about the bushing and its packing from the high pressure side of the pump within the casing 58 to the low pressure side at the intake opening 55. This interferes with the intake of water to the pump, and with the bushing and packing replaceable this condition may be readily and easily rectified whenever it occurs. It will be noted that the bushing 58 is releasably fastened in place through the primer by the bolt 60. The packing may be replaced by releasing its holding ring 73 which is fastened to the cover 62.

40 The details of construction shown and described may be variously changed and modified without departing from the spirit and scope of my invention.

45 I claim as my invention:

1. A portable pumping unit of the character described, comprising a housing and a pumping assembly at its lower end and a motor assembly for operating the pump adjacent the upper end of the housing, and a shaft journaled in the housing between the motor and the pump and providing a driving connection between them, a stuffing box in the housing for the shaft, said box having an outer casing slidably fitted in the housing about the shaft, an anti-friction bearing for the shaft carried by said casing, and means fitted in the housing between the motor and the stuffing box to hold the bearing in the casing and the casing in the housing.

2. A portable pumping unit of the character described, comprising a pump assembly at the lower end of the unit, said pump assembly having

5 a casing and a rotary impeller therein, said casing having a discharge port, said impeller having flange means extending downwardly through an opening in the bottom wall of the casing and providing an intake port for the pump, a motor included in the unit for operating the impeller, a primer for the pump located below said intake port, said primer having a scoop and a fluid passage to serve said intake port, and means for securing the primer to the impeller by clamping it 10 against the outer end of said flange means.

15 3. A portable pumping unit of the character described, comprising a pump assembly at the lower end of the unit, said pump assembly having a casing and a rotary impeller therein, said casing having a discharge port, said impeller having flange means extending downwardly through an opening in the bottom wall of the casing and providing an intake port for the pump, a motor included in the unit for operating the impeller, 20 a primer for the pump consisting of an annular member fitting over the intake port below said flange means, said primer having a scoop and a fluid passage to serve said intake port, and a fastening member extending axially through said 25 intake port and engaging the primer and the impeller for securing the primer to the impeller by clamping the primer against said flange means.

25 4. A portable pumping unit of the character described, comprising a pump assembly at the lower end of the unit, said pump assembly having a casing and a rotary impeller therein, said casing having a discharge port, said impeller having flange means extending downwardly through an opening in the bottom wall of the casing and 30 providing an intake port for the pump, a motor included in the unit for operating the impeller, a primer for the pump consisting of an annular member fitting over the intake port below said flange means, said primer having a scoop and a fluid 35 passage to serve the intake port, means for securing the primer to the impeller, and a housing for the primer secured to the pump casing below the same, said housing having upper and lower plates secured together in vertically spaced 40 relation, and a screen fitted between said plates about the primer, said upper plate having a portion fitting about the opening in the bottom wall of the pump casing and engaging and surrounding the flange means of the impeller.

45 5. A portable pumping unit of the character described, comprising a housing, a rotary pump at the lower end of the housing and a pneumatically operated motor at the upper end of the housing, a shaft journaled in the housing between the 50 motor and the pump and providing a driving connection between them, said housing having a chamber surrounding the shaft between the motor and the pump, said housing having an opening in its outer wall connected with said chamber, a 55 cover slidably mounted on the housing over said opening by having hooked shaped portions at the sides of the cover engaging over outwardly projecting longitudinal ribs on the housing on opposite sides of said opening, said cover having one or more vent holes therein to vent the chamber of any pressure fluid entering the chamber from the motor along the shaft, and a fastening member carried by the cover and engaging the 60 housing for releasably holding the cover in closed 65 position over the opening.

6. A portable pumping unit of the character described, comprising a pump assembly at the lower end of the unit, said assembly having a casing and a rotary impeller therein, said casing having

- ing a discharge port, said impeller having an annular flange providing an intake port for the impeller and extending downwardly through an opening in the bottom wall of the casing, a 5 motor included in the unit and connected with the impeller for operating the same, a packing assembly for said flange at said opening and including a removably mounted wear bushing fitting about and in engagement with said flange, 10 a primer for the pump located below said flange, and means releasably securing the primer to the impeller for rotation therewith, said means securing the primer against the wear bushing for clamping the latter against the impeller.
- 15 7. A portable pumping unit of the character described, comprising a pump assembly at the lower end of the unit, said assembly having a casing and a rotary impeller therein, said casing

having a discharge port, said impeller having an annular flange providing an intake port for the impeller and extending downwardly through an opening in the bottom wall of the casing, a motor included in the unit and connected with the impeller for operating the same, a packing assembly for said flange at said opening and including a removably mounted wear bushing fitting about and in engagement with said flange, a primer for the pump located below said flange, and 10 means releasably securing the primer to the impeller for rotation therewith, said means passing through the intake port as provided by said flange and securing the primer against the outer end of the wear bushing for clamping the latter 15 against the impeller.

REINHOLD A. NORLING.
